UNITED STATES PATENT OFFICE.

ARTHUR T. GOLNIK, OF NEW YORK, N. Y., ASSIGNOR OF ONE-HALF TO EDITH P. WOOD, OF NEW YORK, N. Y.

TOY.

Original application filed November 1, 1924, Serial No. 747,224. Divided and this application filed December 23, 1925. Serial No. 77,183.

This invention relates to novel improvements in toys embracing musical devices and animal character representing devices, and comprises subject matter divided out of my 5 co-pending application Serial No. 747,224, filed November 1, 1924.

Among the objects of the present invention it is aimed to provide a toy having a musical device or sound producing device, 10 which device is either formed to represent the body portion of an animal character or enclosed in a housing representing the body portion of an animal character, and such body forming portion supported by elements 15 representing distinctive portions of animal characters.

Specifically, the present invention contemplates the provision of supports preferably composed of cardboard, celluloid or other 20 sheet-like material cut out to define in outline, one, the front portion of an animate character such as a child or adult in crawling position or an animal character in standing position, and the other, the rear portion 25 of an animate character such as a child or adult in crawling position or an animal character in standing position, and a body portion supported between such supports to represent the body portion of the animate 30 character, and such body portion consisting of a musical device or a sound producing device, or consisting of a housing for a musical device or a sound producing device. Preferably the front and rear sheet-like members 35 representing distinctive portions of animate characters are provided with decorative effects to co-operate with the outline of these elements to produce the distinctive portions of the animate character sought to be represented. 40

These and other features, capabilities and advantages of the invention will appear from the subjoined detail description of certain embodiments of the invention illustrated 45 in the accompanying drawings, in which—

Figure 1 is a front elevation of one of the embodiments of the invention;

Fig. 2 is a side elevation of the embodiment illustrated in Fig. 1;

Fig. 3 is a front elevation of another embodiment of the invention; and

Fig. 4 is a side elevation of the embodiment illustrated in Fig. 3.

Referring now more particularly to the 50 reference characters in the drawing nu-

meral 1 represents a toy, in this case having the configuration of a cat. This toy cat as indicated clearly in Fig. 2 is composed of three main sections, the foremost portion 2 is indicated as the head and the legs of Fig. 60 1, and the rearmost portion 3 is indicated by the tail in Fig. 1, and the rear legs, not shown. These supports may be formed of material such as cardboard, celluloid, wood or metal, the specific material going into the 65 formation of the said supports not being of the essence though it is contemplated to provide these supports of relatively thin configuration and light material of which pressed cardboard forms a readily applicable 70 material.

Between the supports 2 and 3 and directly connected thereto at their extremities there is formed a housing 4. In the modification of Fig. 2 the housing 4 forming a 75 bellows consists of a container or tubular member 5 having in this case a musical source or sound producing device therein which source is actuated by the motion of the housing which in this case is made of collapsible 80 material and held in open or spread position normally to space the supports apart and to form the body of the animal or character by the spring 6. To provide decorative effects there is fixed about the forward support 85 of the animal a ribbon 7 having a bell or other trinket 8 thereon. The forward and rear supports are painted or printed to indicate the color and characteristics of the animal or character to be described, in Figs. 90 1 and 2, 9 indicating the forelegs of the forward support 2 of a cat, whereas 10 depicts the tail or rearward appendages of the animal extending from the rear support 3. 95

In the modification shown in Figs. 3 and 4 there is portrayed an animal, in this case a dog, 11, having forward portions 12, rearward portions 13, and a head portion 17. In this modification there is attached to the upper portion of the support 12 a casing 14 which is covered by a decorative ribbon 15 and which has fastened thereto a spring 16. This spring 16 has fixed at its opposite end the head portion 17 of the dog whereby the head may be moved in various positions so as to give a grotesque appearance to the toy and allow the head to be movable forward at will due to its flexible connection. The housing 18 in this case is fastened in 100 105 110 115

rectly to the two supports 12 and 13 and has therein an opening, in this case containing a musical instrument 19.

Although the devices concerning the invention are herein limited to description of a few members of the animal kingdom it is contemplated within the scope of this invention to include any and all animals.

It is obvious that various changes and modifications may be made to the details of construction without departing from the general spirit of the invention as set forth in the appended claims.

I claim:

15. 1. In a device of the kind described, a pair of supports each composed of a sheet-like material and parallel to one another, one of said supports representing a distinctive portion of an animal character, the 20 other of said supports representing another distinctive portion of such animal character, a bellows extending from one support to the other and representing the body portion of the animal character, and a sound 25 producing device operatively associated with said bellows to function upon actuation of said bellows.

2. A combination figure toy and housing having two supports defining the rearward 30 and forward portions of a four-legged animal character in standing position, the supports being composed of a sheet-like mate-

rial and parallel to one another, the rearward portion having lower extensions defining the rear legs of the animal character 35 in standing position and the forward portion having lower extensions defining the front legs of the animal character in standing position, and a tubular housing extending from one support to the other and constituting a carrier for a sound producing device, one end of the housing being connected to one support and the other end of the housing being connected to the other support and spaced from the supporting 40 surface by the leg portions of said supports.

3. In a device of the kind described, a pair of supports, one of said supports representing a distinctive portion of an animate character, the other of said supports 50 representing another distinctive portion of an animate character, a bellows having a collapsible tubular member, one end of said tubular member being connected to one of said supports and the other end connected 55 to the other of said supports, a spring for normally spacing said supports from one another and normally maintaining said tubular member in extended position to form the body portion of the animate character, 60 and a sound producing device operatively associated with said bellows to function upon the actuation of said bellows.

ARTHUR T. GOLNIK.
